[57] CLAIM

The ornamental design for a combined multi-paneled easel and art display case, as shown and described.

DESCRIPTION

FIG. 1 is a top, left front perspective view of a combined multi-paneled easel and art display case showing my new design;

FIG. 2 is a front elevational view thereof;

FIG. 3 is a left side elevational view, the right side being a mirror image thereof;

FIG. 4 is a top plan view thereof;

FIG. 5 is a rear elevational view thereof;

FIG. 6 is a bottom plan view thereof;

FIG. 7 is a front elevational view in a partially opened condition;

FIG. 8 is a front elevational view in a fully opened condition; and,

FIG. 9 is a front elevational view thereof in an alternate partially opened condition.

FIG. 1

FIG. 2

FIG. 3

FIG. 4
